Primary Examiner—Freda Nunn
Attorney, Agent, or Firm—Banner & Witcoff, Ltd.**[57] CLAIM**

The ornamental design for an electronic computer, as shown and described.

DESCRIPTION

- FIG. 1 is a top, front and right side perspective view of an electronic computer showing our new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view thereof;
 FIG. 7 is a left side elevational view thereof;
 FIG. 8 is a top plan view in a closed position thereof;
 FIG. 9 is a front elevational view in the closed position thereof; and,
 FIG. 10 is a right side elevational view in the closed position thereof.
